UNITED STATES PATENT OFFICE.

DAVID C. RALSTON, OF DETROIT, MICHIGAN.

SOAP PRESSING AND STAMPING MACHINE.

SPECIFICATION forming part of Letters Patent No. 517,064, dated March 27, 1894.

Application filed January 13, 1894. Serial No. 496,745. (No model.)

To all whom it may concern:

Be it known that I, DAVID C. RALSTON, a citizen of the United States, residing at Detroit, county of Wayne, State of Michigan, 5 have invented a certain new and useful Improvement in Soap Pressing and Stamping Machines; and I declare the following to be a full, clear, and exact description of the invention, such as will enable others skilled in the 10 art to which it appertains to make and use the same, reference being had to the accompanying drawings, which form a part of this specification.

My invention has for its object, an automatic power soap pressing and stamping machine of novel construction, and it consists of the combinations of devices and appliances, their construction, arrangement and operation, as hereinafter described and claimed and 20 illustrated in the accompanying drawings, in which—

Figure 1 is a front elevation. Fig. 2 is a vertical section on the line 2—2, Fig. 1. Fig. 3 is a vertical section of the die-box. Fig. 4 25 is a rear elevation. Fig. 5 is a partial side elevation: and Fig. 6 is a plan view of the die-box and of the feeding discharge track. Fig. 7 is a cross section of the wedges P and P².

I carry out my invention as follows:—

30 A represents any suitable support. A' is a table on said support, and A² represents a metal body bolted to the table as shown at "a."

B denotes a driving shaft, which may be 35 driven by any suitable means as by a belt B', the shaft being provided with loose and tight pulleys, as shown at a'.

B² is a bearing upon which one end of the driving shaft is supported. The opposite 40 end of the driving shaft is shown journaled upon standards B³ and B⁴.

I prefer that the driving shaft should be 45 constructed with a cranked portion, as shown at B⁵, located between standards B³ and B⁴. C denotes a perpendicular reciprocating plunger to which a male die "c" is removably 50 attached. The plunger is made reciprocating in suitable grooves or guideways in the body A² as indicated in the drawings at a'.

D represents an angular or bell-crank lever, by which motion is imparted to the plunger, said lever being fulcrumed as indicated

at d, upon the body A². The upper extremity of said lever is engaged with said plunger in any suitable manner, as for example, 55 the plunger may be recessed, as indicated in Fig. 2 at "c'," to admit the upper end of said lever. It will thus be seen, that as the lever D is operated, the plunger will be vertically reciprocated. I do not limit myself solely to 60 any particular means for operating said bell-crank lever, but as shown, the lower end of said lever, is connected by a rod D' to the cranked portion B⁵ of the shaft.

E is a die box, supported upon the table A', 65 in which the soap is pressed. Within the die box is engaged a movable die F, which is made reciprocatory in the die box in any suitable manner.

As shown, the die F is reciprocated in the 70 die box in the following manner:—G is a rotatable shaft geared with the driving shaft as indicated at G' as by suitable gears g and g'. Upon the opposite end of the shaft G is a cam-shaped disk G², rotated by said shaft. As 75 shown, said disk is provided with a cam-shaped spur g².

H, is an oscillatory bar or lever fulcrumed at one end as shown at "h" upon a portion of the supporting device A, the opposite end of 80 said oscillatory bar, riding upon the periphery of the cam shaped disk G². It will be seen by reference to Fig. 1, especially, that when said disk is rotated in the direction indicated by the arrow, the adjacent end of the bar H will 85 ride upon the periphery of the disk, and rise upon the spur g² until the bar is free to drop when the spur has passed from in under said bar.

The spur is so constructed as to permit a quick dropping of the bar H as the spur 90 rides out from in under the free end of said bar. The die F is connected with a vertically movable shaft I, engaged with the oscillatory lever H in any suitable manner. Thus for example, the bar "I" may be provided 95 with collars i and i', between which the bar H is passed. J is a stop block at the base of the bar I. By this construction it will be apparent, that when the free end of the lever H rides upon the upper edge of the spur g², 100 in the rotation of the disk G², the rod I will be lifted carrying the die F upward. When the free end of the bar H rides off from the spur g² the bar I will quickly drop, carrying

the die F into its normal position. Thus, it will be obvious, the die F will be gradually raised, and for the sake of expediting the work, quickly dropped to the base of the die box E. I prefer that the cam-shaped spur should be so arranged with relation to the operation of the upper plunger that the lower die shall drop to the base of the die box before the upper die or plunger has reached its upper point. This operation gives more time for feeding the unpressed bar into the die box.

K represents a spring actuated pressure bar, arranged to catch a bar of soap when the bar of soap is raised out of the die box after being pressed, to support the bar of soap while it is being driven out of the die box into the discharge track or conduit and a new bar of soap is coming into the die box to be pressed. As shown, the bar K is united by a connecting rod K' to an oscillatory bar K² fulcrumed on its lower end at k, a spring K³ connecting the upper end of the lever K² to an adjacent portion of the body A² as shown. The die F is lifted as hereinbefore described to raise a bar of soap after it has been pressed, to discharge the soap from the die box. The bar of soap when lifted is engaged by the pressure bar K and held uplifted when the die F descends. Opposite the pressure bar K is a stationary bar K³, the bar of soap when lifted being retained between the bars K and K³, until crowded out by the entrance of a new bar into the die box, as hereinafter described. The bar K³ is engaged with the upper edge of the die box.

L denotes a feed box, in which the unpressed soap is placed.

M represents a feeding conduit at the base of the feed box L, arranged to feed the unpressed soap in to the die box, and M' is a discharge conduit or track on which the soap is discharged when pressed.

M² is a feeding slide having a reciprocatory engagement in the feeding conduit or track M and arranged to force the unpressed soap from the base of the feed box L, into the die box. The slide M² may be reciprocated in any suitable manner. Thus, as shown, said slide is engaged with an oscillatory lever N, which may be fulcrumed at its base "n" to the base of the support A.

N' is an operating bar—eccentrically engaged with the cam-disk G² as shown at n'. By this construction it will be seen that the feeding slide will be reciprocated by the rotation of the cam-disk G².

It will be understood that the feeding bar or slide, M², pushes the under-most bar in the feed box L in to the die box, and at the same time forces into the discharging slide or conduit M', the previously pressed bar of soap temporarily held between the bars K and K³, upon the descent of the die F. At the same time, while driving in to the die box the under-most bar of soap in the feed box L, the driving slide bar receives and supports the column of bars in the feed box, until the backward

stroke of the driving slide bar is completed, when said column falls, placing another bar in position in front of the driving slide, ready for the next forward movement of the driving slide. For greater convenience in supplying the feed box L, it is preferably arched slightly as shown more particularly in Figs. 2 and 5.

For regulating the amount of pressure to be applied to the bars of soap, while being pressed between the dies "c" and F, I prefer to provide a wedge P and a screw P' connected therewith to operate the wedge. In the die box E, is a loose wedge P². The screw P', works through a suitable bracket a³. This arrangement of devices connected with the die box readily permits the die F to be raised or lowered as may be required to secure exactly the degree of pressure desired. In case greater adjustment is required than can be made by these wedges, solid plates may be placed under the bottom die above the wedge P². Both the wedges and the plates are slotted to permit a free passage of the die stem or rod I.

To obviate any liability from a bar of soap which is short in length, in not fully discharging the previously pressed bar, and thus allowing the upper die to cut off a portion of the pressed bar, and thus gumming up the dies with mashed soap, the discharge conduit M' is caused to move at each stroke of the die "c," a distance sufficient to be entirely out of reach of the descending die "c." This movement of the discharge conduit M' may be effected as follows: At the upper end of the plunger C is pivotally connected a rod Q, said rod being also pivotally connected with an oscillatory bar Q' fulcrumed upon a suitable support Q² as shown at q, the bar Q' being connected as shown at q' with the discharge box or conduit M'. It will be evident that when the plunger C descends the upper end of the bar Q' will be forced laterally carrying the discharge box M' proportionately therewith. In this manner the discharge box will be moved backwardly and away from the descending die "c" and out of reach thereof. The discharge box returns promptly in to position to receive the next bar when the plunger C is lifted.

The operation of the device will now be understood. The feed box L having been filled with soap, power is applied to the driving shaft B, which in turn rotates the shaft G operating the lower die and also the upper die, together with the feeding slide, and other portions of the device. The undermost bar of soap is forced by the forward stroke of the feeding slide between the pressure bar K and the opposite bar K³, and the previously pressed bar of soap is discharged thereby upon the discharge box. The unpressed bar of soap thus fed under the die "c" is forced by the descent of the plunger C into the die box upon the die F, pressing the bar of soap. The die "c" then rises, as does also the lower

die F at the same time, as hereinbefore explained. The newly pressed bar of soap is thus raised between the pressure bar K and the bar K³ where it is held until forced into 5 the discharge box M' by the next forward movement of the feeding slide M². Thus every revolution of the driving shaft presses and discharges a bar or cake of soap into the discharge box M', each newly pressed bar or 10 cake pushing the previously pressed bar ahead into the discharge box. A continuous line of pressed bars of soap is thus delivered into the discharge box, which may be received upon an endless belt and carried to wrapping 15 tables, or to the boxing department as required, in any ordinary manner. The spring tension pressure bar K also serves to steady the delivery of an unpressed bar from the feeding slide exactly under the upper die, as when going 20 at a high rate of speed, without such a check, the unpressed bar would be liable to jump further than actually pushed by the feed bar. The spring tension on the pressure bar K however, effectually prevents such liability and 25 holds the unpressed bar under the upper die exactly where it is delivered by the feed bar. The exact delivery of the feeding bar may be regulated in any suitable manner, as by means of set screws R.

30 The machine is evidently of superior efficiency, while also its operation is simple and expeditious.

31 Normally the pressure bar K extends forward of the adjacent edge of the descending die "c" when in position to hold a cake of soap, but it is moved back out of the way when said die descends in any suitable manner. Thus upon the bell crank lever D may be formed a stop or lug "d" which strikes

32 against the bar K² in the operation of the lever D, forcing the rod K' and pressure bar K to reciprocate simultaneously with the action of the upper die.

I prefer to construct the upper wedge P^2 with lateral flanges shown in Fig. 7 at "p" and p' , the wedge P fitted in between said flanges. By this construction, if the wedge P is removed too far, the flanges "p" "p'" support the upper wedge in a horizontal position.

5° What I claim as my invention is--

1. In a soap pressing and stamping machine, the combination of a feeding box, a stationary feeding conduit, communicating with the base of said box, a discharge conduit or track, a die box located between the feeding conduit and the discharge conduit, upper and lower reciprocating dies arranged to press the soap in the die box and to discharge it therefrom, and a reciprocating feeding slide located in the feeding conduit to feed the unpressed soap into the die box, substantially as set forth.

2. In a soap pressing and stamping machine, the combination of a die box, upper and lower reciprocatory dies arranged to press the soap in said die box and to lift the soap

therefrom, a spring tension pressure bar, located at the upper end of the die box, and a stationary bar located opposite the pressure bar substantially as and for the purpose described. 70

3. In a soap pressing and stamping machine, the combination of a die box, reciprocating dies, a feeding conduit and a discharge conduit, the discharge conduit simultaneously movable with one of said dies, substantially as set forth. 75

4. In a soap pressing and stamping machine, the combination of a die box, upper and lower reciprocatory dies, a feeding conduit and a discharging conduit, a feeding box and a feeding slide having a reciprocatory engagement in the feeding conduit, the feeding slide arranged to force an unpressed bar of soap into the die box and to support the unpressed bar in the feeding box, the lower die dropping to the base of the die box before the upper die has reached its highest point, substantially as set forth. 80 85

5. In a soap pressing and stamping machine, the combination of a die box, a lower reciprocating die and an upper reciprocating die, a pressure bar located at the top of the die box, a spring tension lever K², and a rod connecting the pressure bar with said lever, 95 substantially as set forth.

6. In a soap pressing and stamping machine, the combination of a die box, an upper reciprocator die, a lower reciprocator die provided with a supporting rod, and slotted adjusting wedges $P P^2$ at the base of the die box to control the pressure of the dies, substantially as set forth. 100

7. In a soap pressing and stamping machine, having in combination a die box, reciprocal dies, a bell crank lever connected with the upper die, a cranked driving shaft to operate said lever, a shaft G driven from the driving shaft and provided with a cam-disk G², and an oscillatory bar H, riding on the periphery of the cam-disk to operate the lower die, substantially as set forth. 105 110

8. A soap pressing and stamping machine, having in combination a die box, reciprocatory dies, a driving shaft to operate the upper die, a shaft G, driven from the driving shaft and provided with a cam-disk G², and an oscillatory bar H, riding on the periphery of the cam-disk to operate the lower die, the cam-disk constructed to gradually lift the bar on its periphery to raise the lower die and to instantly drop said bar to lower said die, the lower die being dropped to the base of the die box before the upper die has reached the limit of its upward stroke, substantially as set forth. 115 120 125

9. In a soap pressing and stamping machine, the combination of a die box, upper and lower reciprocatory dies arranged to press the soap in said die box and lift the soap therefrom, a pressure bar located at the upper ends of the die box and a stationary bar

located opposite the pressure bar, said pressure bar being simultaneously movable with the upper die, substantially as set forth.

10. In a soap pressing and stamping machine, the combination of a die box, upper and lower reciprocatory dies, a feed box, a feed conduit, a reciprocatory slide in said conduit, a movable discharge conduit, and a movable spring pressure bar to hold the soap in

lifted position ready to be discharged upon the discharge conduit, substantially as set forth.

In testimony whereof I sign this specification in the presence of two witnesses.

DAVID C. RALSTON.
